UNITED STATES PATENT OFFICE

ARTHUR ATWATER KENT, OF ARDMORE, PENNSYLVANIA

DESIGN FOR A CABINET FOR RADIO RECEIVING APPARATUS

Application filed September 4, 1930. Serial No. 36,859. Term of patent 7 years.

To all whom it may concern:

Be it known that I, ARTHUR ATWATER KENT, a citizen of the United States, residing at Ardmore, county of Montgomery, State of Pennsylvania, have invented a new, original, and ornamental Design for a Cabinet for Radio Receiving Apparatus, of which the following is a specification, reference being had to the accompanying drawing, forming part hereof.

The figure is a perspective front view of a cabinet showing my design.

My ornamental design discloses a low boy type of radio cabinet having a single beaded offset horizontal bar at the junction of the top and side panels and a single beaded substantially reeded bar at the bottom of the side panels.

I claim:

The ornamental design for a cabinet for radio receiving apparatus, as shown and described.

ARTHUR ATWATER KENT.
